CLAIM

The ornamental design for an ice pack for a breast pump, as shown and described.

DESCRIPTION

FIG. 1 is a front view of an ice pack for a breast pump

FIG. 2 is a rear view thereof;

FIG. 3 is a bottom view thereof;

FIG. 4 is a top view thereof;

FIG. 5 is a right side view thereof; and,

FIG. 6 is an elevated front perspective view thereof.

The right side view substantially mirrors the left side view. The dashed lines in the figures form no part of the claimed design.

1 Claim, 4 Drawing Sheets
